TELEVISION APPARATUS

Harry R. Lubcke, Los Angeles, Calif., assignor to
 Don Lee Broadcasting System, Los Angeles,
 Calif., a corporation of California

Application March 23, 1938, Serial No. 197,637

11 Claims. (Cl. 178—7.1)

My invention relates to the art of television, and particularly to methods and means for scanning motion picture films by the use of mechanical equipment.

5 It is well known that practical limitations, as to smallness and accuracy of placement of the holes in scanning disks, seldom allow entirely satisfactory results where disk scanning is used for high definition television, as when images of 300 10 to 441 lines are desirable. The principal object of the present invention, therefore, is to provide a simple optical system for avoiding the effect of such limitations in television reproduction.

Subsidiary objects, all of which contribute to 15 the attainment of said principal object, include; first, provision of much smaller effective optical apertures in disk scanning than are attainable by the use of physical apertures in the ordinary manner; second, to provide means for adjusting 20 the size of such optical apertures over a wide range, without changing the physical apertures; third, to make it feasible to employ a set of physical apertures, for securing small effective optical apertures for image scanning, coincidently with 25 much larger effective apertures for generating synchronizing pulses; and, fourth, to devise a practical method for initiating a synchronizing pulse immediately preceding each image scan, said pulses occurring always at a definitely fixed 30 time interval before the image scan begins.

My objects have been attained in the manner illustrated in the accompanying drawing, in which—

Figure 1 is a much enlarged fragmentary cross-section of an ordinary scanning disk, in the plane of the axis of a typical scanning aperture therethrough;

Figure 2 is a view of the right hand face of said disk fragment, when looking in the direction of angle α from the perpendicular;

Figure 3 is a diagrammatic illustration of the complete optical system of the present invention in elevation;

Figure 4 is a diagrammatic illustration of said 45 system in plan;

Figure 5 is a fragmentary face view of a scanning disk which is faulty by reason of unequally spaced scanning apertures, in aid of the discussion to follow regarding the effect of such spacing;

Figure 6 is a large scale diagrammatic illustration of a portion of the screen of a cathode ray tube, while it is reproducing a television image initially scanned by a disk having the faults exhibited by Fig. 5; the reproduction being synchro-

nized by pulses occurring at equal time intervals; and

Figure 7 is a similar diagrammatic illustration of said screen while it is reproducing an image initially scanned by said faulty disk, but with the reproduction synchronized by pulses produced by the same apertures that were used in the initial image scanning.

Certain of the illustrated proportions have been considerably exaggerated, for convenience 10 in this disclosure. Similar reference characters refer to similar things throughout the several figures of the drawing.

The body of a mechanical scanning disk is shown at 8 in the drawing, both pictorially and 15 diagrammatically. The disk is assumed to be rotatable about its axis 9, in the direction of arrow 11. Such a disk always is provided with a large number of spaced cylindrical scanning apertures therethrough, of which three are indicated in Fig. 5 at 12, 13 and 14 respectively.

Figure 1 shows a relatively thick scanning disk fragment, on a greatly enlarged scale, with such a scanning aperture therethrough. The working portion of this aperture is cylindrical, as at 15; 20 and we will assume that its cross-sectional area is correctly represented by A, its diameter by D, and its axial length by T. In cases like this, countersinking of the scanning holes is required, as at 16, to secure holes of the desired length. If 25 the disk were made of thickness T at the scanning holes, no such countersinking would be required, of course; but, as a practical matter, such a disk would be too thin, and thus be subject to mechanical distortion. Countersinking the holes 30 overcomes this difficulty, the shape of the countersinking being immaterial so long as it entails no obstruction to rays emerging from the cylindrical portion of the apertures.

Such physical apertures afford the possibility 40 of using greatly decreased optical apertures; by properly proportioning their axial lengths and diameters, and by causing light to impinge thereon at an advantageous angle from the perpendicular, which angle will herein be designated as α . 45 It should be remembered, however, that the useful light transmitted through disk apertures must come from only one elemental area of the scene being scanned at every instant. Light which is reflected from the walls of the apertures does not 50 meet this requirement, and must not be permitted to reach the means employed for television transmission. All of this will be explained more fully below.

In the use of a preferred embodiment of the 55

present invention, an optical image of a scene is transmitted. In other words, the scene to be transmitted is represented by light which is modulated as to intensity over an area. Such embodiment is illustrated diagrammatically in Figs. 3 and 4, in elevation and plan respectively. In these two figures, light from a source 17 is indicated as being transmitted through a motion picture film 18, and focused upon a scanning disk 8 by means of objective lens 19. This light falls upon the disk at an angle α from the perpendicular, and the front face of the disk, at the zone of the scanning holes, thus becomes flooded with image modulated light.

15 By referring now to Fig. 1 it will be seen that only light within the beam $d-d'$ can pass directly through the scanning hole. The cross-section of this beam is the same as the overlapping portions of the projected areas of the two 20 ends of aperture 15 when seen in the direction of the beam, and hence is represented by the small area a of Fig. 2. Other light entering aperture 15 will be reflected from the wall thereof, in the manner indicated by the beam $r-r'$.

25 Of all the possible values of numerics D , T and α , the optimum results are obtained when $T=2D$ and $\alpha=22\frac{1}{2}^\circ$. Figs. 1, 2 and 3 have been drawn to this criterion. This relation does not allow of multiple reflection within aperture 15; 30 and the cross-section of the effective image aperture, represented by numeric a ; is the smallest obtainable with the given physical aperture and angle of incidence. The angle between direct ray $d-d'$ and the reflected portion of $r-r'$, is 35 45° under such conditions.

It is important to prevent multiple reflection from the wall of aperture 15 to the greatest possible extent, because any reflected light which should leave the aperture in a direction near 40 enough to that of the direct beam to impinge on image transmission devices, would cause proportional blurring of the received image. This is for the reason that the reflected rays necessarily originate at different parts of the image from 45 the source of the direct rays; and the reflected rays cannot be wholly eliminated by blackening or otherwise treating the interior surface of aperture 15. Almost any surface will reflect considerable light at the small reflection angles occurring in such apparatus as we are considering.

50 It is desirable that the effective image aperture be made as small as possible, to permit of securing greater definition in the transmitted image; but the use of relatively large physical apertures increases the precision with which the scanning disk can be made. Although the smallest practical drill should be used for the disk apertures, so that the overall dimensions of the 55 equipment may be kept within reasonable limits; the accuracy with which small holes may be positioned, and their size be maintained invariable, decreases with the size of the drill used. By employing my method of using a scanning beam 60 which is oblique to the axes of the scanning apertures, it is possible to obtain an effective image aperture having a cross-section area which is but a small fraction of that of the smallest physical aperture that is attainable. It is entirely feasible to secure, in this manner, a ratio 65 between cross-sectional areas of the order of 1 to 25.

70 It is desirable that the angle between the direct and reflected light beams be great, as of the order of 45°, to enable the image transmitting

means to be positioned so as not to intercept reflected rays.

75 It is easily possible to vary the relation between the cross-sections of the effective and physical apertures, a and A respectively, by changing either the angle of incidence α , or the length T of the physical aperture. Effective aperture size and shape may thus be adjusted by merely tilting the base of the projecting apparatus, and no structural changes are required.

10 It will be noted that the major axis of area a is parallel to the direction of scanning, and that this area possesses a very desirable shape for a scanning spot. Spurious patterns do not occur so readily in the reproduced field of view, when such a spot is used, as when rectangular scanning apertures are employed.

15 The emergent image scanning beam $d-d'$ is focused upon a photoelectric device 21, by means of a lens 22, for actuating the image transmission apparatus.

20 In Figs. 3 and 4, means for producing the necessary high frequency (or "line") synchronizing pulses are diagrammatically illustrated. For such synchronization I focus light from a 25 source 23 perpendicularly upon the surface of disk 8, by means of a lens 24, and allow the beam to pass through the scanning apertures parallel to the axes thereof, I thus utilize the entire cross-section of the apertures for producing the synchronizing pulses. The duration of the latter is two or three times as long as the time required for scanning one elemental area of the image field of view, which is desirable. The optical efficiency of this pulse producing means is many 30 times larger than it would be if only the effective image aperture (of cross-section a) were utilized.

35 A 100 watt lamp may be used at 23, and an image of its filament is focused upon the surface of disk 8 in the aperture zone, by means of lens 24. Lens 25 concentrates the light emerging from the apertures upon a photoelectric device 26, for initiating the high frequency synchronizing pulses. By increasing the width of the filament image on the disk, in a tangential direction, 45 by employing a wider actual filament, the duration of the high frequency synchronizing pulse may efficiently be made as long as reasonably desirable. Elements 23, 24, 25 and 26 are in alignment as indicated by the line $p-p'$, and the latter coincides with the axes of the physical apertures at their upper central positions.

40 The advantage of having a pulse aperture materially larger than the effective image aperture, will be appreciated by those familiar with the art, in view of what has been said.

50 Means for producing the low frequency synchronizing pulses, and the character of the amplifiers, radio transmitter, receiver, cathode ray tube, and of the scanning devices required to 55 complete the television system, are fully illustrated and described in my U. S. Patent No. 2,055,748, issued September 29, 1936. They form no part of the present invention, and need not be further considered herein.

60 According to the present invention, it is necessary to have only one ring of apertures in disk 8; and this single set of apertures may be utilized both for image scanning and high frequency pulse production, in the manner described. Such utilization makes it impossible for time displacements to occur as between scanning and pulse production. No dependence upon precision of construction and mechanical skill is necessary; and, at the same time, the highest definition re- 65 70 75 80 85 90 95

quirements of satisfactory television are attainable.

By referring to Fig. 4, it will be noted that, sequentially, the pulse optical system (represented by elements 23 to 26) is located before the image optical system (represented by elements 17 to 21). As each and every disk aperture functions, it first serves to initiate a synchronizing pulse, and immediately thereafter to scan a line across the image. The time interval between these two functions is necessarily fixed and constant, by reason of the constant speed of the scanning disk. Inaccuracies in spacing the disk holes therefore are of no particular consequence.

Fig. 5 shows a portion of a scanning disk having three inaccurately spaced apertures 12, 13 and 14 therethrough; and a simple optical image, comprising bars 27 and 28 of different width, is represented as being focused upon the face of the disk. The inaccuracy of spacing the scanning apertures has been exaggerated, for convenience of illustration. As the disk revolves in the direction of arrow 11, aperture 14 will scan bar 27 first, and then bar 28. Such a scan is diagrammatically shown as reproduced on the receiving screen, in Fig. 6 at 29.

Now if disk scanning aperture 13 is positioned to the left of its proper location 31, its scanning will occur later than it should, and ordinarily it would appear on the receiving screen as at 32 in Fig. 6. If scanning aperture 12 is positioned too far to the right of its proper location 33, its scanning will occur too soon, and ordinarily it would appear on the receiving screen as at 34 in Fig. 6.

Fig. 6 thus illustrates the serious type of distortion which occurs in received television images when the synchronization is by pulses which are equally spaced in time. Such distortion is especially noticeable in the case of vertical edges of buildings, and in other places where fine detail is carried over several horizontal scans. Inaccurately placed scanning apertures at present result in inaccurately timed synchronizing pulses, and these are in random relation to the image scanning inaccuracies. Since the algebraic sum of these errors must be considered, it is possible that certain of them will be reduced in effect, or even eliminated; but, in general, the result is worse than indicated in Fig. 6.

In the system of the present invention, a synchronizing pulse always precedes each scan, by exactly the same time interval; and the reproduced image will be entirely free of distortions due to inaccuracies in placing the disk scanning apertures. The fact that one scan at the receiver may be initiated at a slightly different time, or that it may be of slightly different duration, than normal or average, is of no practical consequence. Oscillators which are adapted for television scanning, must be sensitive to synchronization to such an extent as readily to follow the slight irregularities of timing that may be due to ordinary faulty spacing of the disk scanning apertures. Non-oscillating receiver scanning sources, which are actuated by transmitted synchronizing pulses, will inherently be able to keep in step.

Fig. 7 illustrates how received image elements, which have been produced in accordance with the methods of the present invention, appear in relation to their respective scans and to each other. The receiver is brought into step, and made ready for scanning, upon the arrival of each synchronizing pulse. Then, after a short but definitely fixed and constant time interval,

its scanning starts at the left hand side of the field of view, in synchronism with the transmitter scanning. Thus the left margin of the received scene is developed as a straight vertical line. The velocity of the scanning disk at the transmitter is constant, by reason of its inertia. Consequently, because of the concurrence of these influences, each element of the field of view at the receiver is accurately placed with respect to corresponding elements of the scans, both above and below, as shown at 27 and 28 in Fig. 7. It cannot be otherwise, and there is no possibility of maladjustment affecting this result.

The only effect that inaccurate placement of the disk apertures can have upon the received image, is to make the scans of different length, as shown at 35, 36 and 37 of Fig. 7. This will happen because, when such inaccuracies exist, succeeding synchronizing pulses will occur too soon or too late for uniformity. This result, however, can affect detail only at the extreme right hand margin of the scene; and, for nearly every practical purpose, it is entirely negligible.

Attention is particularly directed to the fact that mutual inclination of the axes of the pulse and image systems practically eliminates adverse effects of aberration, reflection, and random light in general. Such inclination, moreover, affords space for placing the optical elements to the best advantage. The lenses may be located close to the focal plane on the scanning disk; and no other refracting, or any reflecting, elements are required. Hence great simplicity, coupled with high efficiency, is attained.

The figures of the appended drawing illustrate disk scanning apparatus wherein the scanning apertures are drilled perpendicularly to the surface of the disk; and the use of an image optical system which is inclined downwardly from a light source to a photoelectric device, at an angle of 22½°. Certain other arrangements are feasible, without departing from the essence of the present invention. Among such variants are:

First, the inclination of the image optical system may be reversed, the path from the light source to the photoelectric device being inclined upwardly instead of downwardly, at an angle of 22½°;

Second, the scanning apertures may be drilled at an angle of 22½° with respect to the axis of the disk, either in a convergent or divergent direction. In this case the image light beam $d-d'$ must be parallel to the axis of the disk, instead of being inclined thereto; and the pulse optical system must be inclined in the same way, and to the same degree, as the scanning apertures;

Third, the axes of the scanning apertures may be oblique to radial planes containing the axis of the disk, as well as to the axis of the disk alone. In such a case, if the latter obliquity is 45°, the cross-section a of the image beam $d-d'$ will have its major axis at an angle of 45° with respect to the direction of scanning. Such positioning of the scanning spot will give greater resolution along each scanning line, but less between adjacent scans, than the originally described arrangement. Moreover, the angular separation between the direct and reflected rays of the image light will be 22½°, instead of 45°; and

Finally, it will be understood that the teachings of this disclosure may be applied to other equipment known to the television art. For instance, the well known type of scanning disk, having one or more spirals of apertures, may take the place of disk 8 described herein. In this case

the apertures are drilled at an angle to the axis of the disk, as outlined in the second variant above, and a synchronizing beam is provided having a radially long, and tangentially narrow, cross-section. This beam is made to impinge upon the surface of the disk from a point within the inner limit of the aperture spiral, to a point without the outer limit of said spiral. Each aperture thus would be adapted to produce a synchronizing pulse as it passes said beam.

Having thus fully disclosed my invention, I claim:

1. Television apparatus comprising; a rotatable scanning disk provided with cylindrical apertures therethrough, the axial length of the apertures being greater than the diameter; and means for projecting radiant energy through each of said apertures in turn, at an angle to its axis, for securing direct energy beams of small cross-section relative to said apertures, while diverting the balance of said energy by reflection from the interior of said apertures at a substantial angle to said direct energy beams.

2. Television apparatus comprising; a rotatable scanning disk provided with cylindrical apertures therethrough, the axial length of the apertures being greater than the diameter; means for projecting image-modulated light through each of said apertures in turn, at an angle to its axis; and a photoelectric device positioned to receive only that portion of said light which passes directly through the apertures, the remainder of said light being reflected from the interior of said apertures and leaving at a substantial angle to said direct light.

3. Television apparatus comprising; a rotatable scanning disk provided with cylindrical apertures therethrough, the axial length of the apertures being twice the diameter thereof; means for projecting image-modulated light through each of said apertures in turn, at an angle of 22½° to its axis; and a photoelectric device positioned to receive only that portion of said light which passes directly through the apertures when so projected.

4. Television apparatus comprising; a rotatable scanning disk provided with cylindrical apertures therethrough, the axial length of the apertures being greater than the diameter; each aperture axis being inclined 22½° to the axis of the disk in a plane which includes both said axes, and also being inclined not more than 45° to said plane.

5. Television apparatus comprising; a rotatable scanning disk provided with cylindrical apertures therethrough, the axial length of the apertures being greater than the diameter; means for projecting image-modulated light through each of said apertures in turn, at an angle to its axis; a photoelectric device positioned to receive only that portion of said light which passes directly through the apertures; means for projecting unmodulated light for synchronization through each of said apertures in turn, in a direction parallel to its axis; and a second photoelectric device positioned to receive said unmodulated light.

6. Television apparatus comprising; a movable scanning member provided with apertures therethrough, the axial length of the apertures being greater than the diameter; means for projecting image-modulated light through each of said apertures in turn, at a substantial angle to the axes thereof; photoelectric means for intercepting

only said light which passes directly through said apertures; and means for projecting light for synchronization through each of said apertures in turn, in a direction substantially parallel to said axes.

7. In television apparatus, means for producing transmittable synchronizing pulses at a fixed time interval before starting each scan of the field of view at the transmitter, comprising; a scanning member provided with apertures therethrough; an optical system for producing said synchronizing pulses; and an image optical system; said two systems being co-operatively related to the scanning member, and their axes being differently inclined with respect to the axes of the apertures of said member, the image optical system being inclined at the greater angle thereto.

8. Television apparatus comprising; a rotatable scanning member provided with apertures therethrough; an image optical system inclined to the axes of said apertures when at their operating positions; and a synchronizing pulse optical system coaxial with said aperture axes at said positions; the pulse system being positioned adjacent to the image system and so that each aperture will coact first with the pulse system and then with the image system, thereby producing a synchronizing pulse the same interval before image scanning begins for each aperture.

9. Television apparatus comprising; a movable scanning member provided with cylindrical apertures therethrough, the axial length of the apertures being greater than the diameter; and means for projecting image-modulated light through each of said apertures in turn, at an angle to its axis, for securing direct light beams of small cross-section relative to said apertures, while diverting the balance of said light by reflection from the interior of said apertures to secure effective optical apertures which are smaller than the physical apertures; the relative sizes of said two kinds of apertures being dependent upon said angle, and adjustable by varying the angle.

10. Television apparatus comprising; a rotatable scanning member provided with cylindrical apertures therethrough, the axial length of the apertures being greater than the diameter; and means for projecting image-modulated light through each of said apertures in turn, at an angle to its axis, for securing direct light beams of small cross-section relative to said apertures, while diverting the balance of said light by reflection from the interior of said apertures to secure effective optical apertures which are smaller than the physical apertures; the relative shape of said two kinds of apertures being dependent upon said angle, and adjustable by varying the angle.

11. Television apparatus comprising; a scanning member having movable apertures therethrough, the axial length of the apertures being greater than the diameter; an image optical system directed obliquely to the axes of said apertures when at their operating positions; and a synchronizing pulse optical system directed parallel to said axes at said positions, including a source of light of substantial emitting area; and means for focusing an image of said source upon a plane, said image having an area greater than the area of one said movable aperture, at a position traversed by said apertures.

HARRY R. LUBCKE.
